UNITED STATES PATENT OFFICE.

BERNARD J. RILEY, OF NEWARK, NEW JERSEY.

IMPROVEMENT IN BAG-LOCKS.

Specification forming part of Letters Patent No. 146,282, dated January 6, 1874; application filed December 16, 1873.

To all whom it may concern:

Be it known that I, BERNARD J. RILEY, of Newark, in the county of Essex and State of New Jersey, have invented a new and useful Improvement in Locks for Traveling-Bags, of which the following is a specification:

Figure 1 is a vertical longitudinal section of the lock-case and top of bag-frame. Fig. 2 is a cross-section of the same, taken at one side of the fastening-standard. Fig. 3 is a longitudinal section on the line $x\ x$, Fig. 1. Fig. 4 is a view of the key-piece removed from the fastening-standard, and Fig. 5 shows the hasp portion of the lock carried on one side of the frame.

The invention consists in the combination, with a spring-supported bolt-piece, of a standard having a guard, and operating in connection with a seat, so that the bolt-piece may be locked or be allowed to move, and in connection with this standard I employ a removable key-piece.

On the drawing, $a\ a'$ represent the top pieces or frames forming the top of a traveling-bag. b is a plate, and c a case to sustain and inclose the mechanism of the lock or fastening, and these parts are confined to the part a' of the bag-frame by suitable rivets or bolts. Rising from and secured to plate b are two headed studs, d , surrounded by spiral springs e . These studs guide, and the springs hold up against the heads, a bolt-piece, f , consisting of a plate provided with one or more short beveled studs, g . A seat, j , having a slot, x , is secured to plate b , which, as well as the top of the frame, is provided with an opening, to allow the passage of standard h , and the seat is placed with respect to such openings so that a portion, p , of plate b serves as a rest under one end of slot x in the seat, for a guard or projection, i , on the standard h , and to prevent the standard h from being depressed. This standard h , having guard i , and supported by the bolt-piece f , is provided, at its upper portion, with a depressing-spring, m , to hold the standard down against the bolt-piece f , and with a screw-thread to receive a screw-threaded projection from a key-piece, o . This key-piece is thus removable. It serves the purpose of a key, and its projecting portion may be of any desired shape, it only being necessary that a proper-shaped opening be made to receive it in the top portion of the

standard h . The part a of the frame has a plate, r , provided with recessed lugs s , that pass through openings made in the side of the case c , in line with the studs g .

The bag being open, the jaws may be closed, when the lugs will pass through the openings in case c , will meet and depress the beveled studs g , and, when the recesses in the lugs come above the ends of the studs, the latter will rise in such recesses under the action of the springs e , and thus confine the two parts $a\ a'$ together.

To open the bag, the standard h should be turned to the position shown in Figs. 1 and 3, so that the guard i is free to pass down through the slot in the seat, and the coinciding openings in the plate b and frame, and in this position the bolt-piece f may be depressed by depressing the standard h .

To lock the bag, and to effectually prevent the disengaging or downward movement of the bolt-piece f , elevate the standard h so that its guard i is above the notch x in the seat j , then turn the standard h half-way around, so that the guard i enters the right-hand end of slot x in the seat, and in this position the portion p of plate b supports standard h , so that it, and with it the bolt-piece f , cannot be depressed.

When the key-piece o is removed from the standard h , the latter cannot be raised and turned by the fingers, as it is entirely within the case c .

This fastening can be easily adapted to sewing-machine covers, pianos, boxes, &c.

Instead of forming the seat as shown, to prevent the standard from being depressed or turned, I may provide it with a projection to enter a recess of the standard h or guard i .

Having described my invention, I claim—

1. The spring-supported bolt-piece, provided with one or more lugs, in combination with the standard provided with a guard depressing-spring, m , and operating in connection with the seat, substantially as described.
2. The combination, with the standard, having a guard depressing-spring, m , and supported on the bolt-piece, of the removable key-piece, substantially as and for the purpose described.
